DOOR LATCH UNIT

Donald S. Harris, New Castle, Ind., assignor to New Castle Products, Inc., New Castle, Ind., a corporation of Indiana

Application May 11, 1956, Serial No. 584,353

12 Claims. (Cl. 70—95)

The present invention relates generally to a new and improved latch unit having a latching member adapted for interlocking cooperation with a catch, which unit is particularly adapted for use with sliding or foldable doors of the type wherein the door jamb carrying the latch unit is moved into contact with a door frame or jamb carrying a catch for locking cooperation with the latching unit. More specifically, the present invention is directed to an improved latching unit having a latching member adapted for locking engagement with a catch upon forcible engagement between the same, the latching member being further adapted upon adjustment of the elements associated therewith for forcible disengagement from the catch.

It is an object of the present invention to provide a latch unit for use with doors, such as sliding or foldable doors, which unit is placed into locking engagement with a catch solely by forcible abutment between the same, and which unit includes adjustable means allowing the same to become forcibly disengaged from the catch when desired.

Another object is to provide a latch unit including a latching member and associated elements cooperating with the latching member to allow the same to become forcibly engaged with a catch and preventing disengagement, forcible or otherwise, of the same without positive operation of an operating knob associated with the latch unit, certain associated elements controlling the functioning of the operating knob to allow fixed positioning of the same permitting forcible engagement and disengagement between the latching member and catch at all times, the force necessary to automatically engage or disengage the latching member with respect to a catch being capable of regulation by adjustable means carried by the unit.

A further object is to provide a latch unit having a latching member mounted for pivotal action with respect to spaced pivot points, the pivotal action about one of the points being limited by means associated with the latching member and movable into and out of association therewith by positioning means included in the unit, the positioning means being capable of adjustment to allow knob operation to move the limiting means into and out of operative association with the latching member in such a manner that the latching member is forcibly disengageable from a catch either at all times or only upon operation of the knob.

Still a further object is to provide a latch unit capable of carrying out the aforementioned objects and which further, upon mounting in a door handle unit, is adapted for association with different forms of key-operated locks thereby allowing the latch unit to be utilized with different forms of door handle units.

Other objects not specifically set forth will become apparent from the following detailed description made in conjunction with the drawings wherein:

Fig. 1 is an elevation of an installed accordion-type foldable door assembly illustrating one form of door with

2

which the latch unit of the present invention is particularly adapted for use;

Fig. 2 is an enlarged horizontal section of the interconnected handle units of the door of Fig. 1 being taken generally along line 2—2 of Fig. 1;

Figs. 3—6 are enlarged side elevational views of the elements of the latch unit of the present invention illustrating their operative relation and the functioning of the same;

Fig. 7 is a plan view in horizontal section of the door jamb and door handle carrying the latch unit and illustrating the elements associated therewith for operating the latch unit as well as one form of locking the same, the view still further illustrating the mounting of a sealing strip along an edge of the door jamb;

Fig. 8 is a fragmentary side elevation partly sectioned illustrating the mounting of a sealing strip along the vertical surface of the door jamb shown in Fig. 7 and further illustrating a modified form of latch locking arrangement;

Fig. 9 is a vertical section of the latch unit taken generally along line 9—9 of Fig. 3;

Fig. 10 is a fragmentary sectional view of a portion of the latch unit taken generally along line 10—10 of Fig. 5;

Fig. 11 is a perspective of a slidable plate forming a part of the latch unit; and

Fig. 12 is a perspective of the latching member of the latch unit.

In Fig. 1 a known type of foldable accordion-pleated door formed from relatively movable sections 15 and 16 is shown. Each of the sections 15 and 16 is movable toward and away from one another on suitable tracks carried by the top cross member of a door frame 17 defining an opening in a wall 18. Each of the door members 15 and 16 is formed from foldable material defining panels 19 which fold upon one another when the door sections 15 and 16 are moved away from one another in opening the same. The abutting edges of the door portions 15 and 16 are provided with door jambs 20 and 21 respectively. The door jamb 20 carries a door handle 22 for grasping and moving the door section 15 toward or away from the door section 16 and the door jamb 21 carries a door handle 23 for a similar purpose, the handle 23 carrying the latch unit of the present invention. The handle 23 externally carries a latch unit operating knob 24 which controls the operation of the latch unit in a manner to be described.

In Fig. 2 the door sections 15 and 16 are illustrated in their closed and interlocked position. The door jamb 20 is formed from a hollow metal post 25 which has received about its outer surface a decorative covering 26 of cloth or plastic material. Each side of the post 25 carries a door handle 22, one of which is provided with integral vertically spaced handle fastening rods 27, one of which is shown, which extend through the interior of the post 25 and into aligned apertures in the oppositely carried door handle 22. The end of the rod 27 received in the opposite door handle 22 is retained therein by a clamping screw 28 cooperating with a grooved portion 29 near the end of the rod 27. The outermost end surface of the post 25 facing the door jamb 21 carries a channel member 30, the outer surface of which is bowed inwardly to form a vertically extending continuous groove 31. The groove 31 is transversely slotted, as indicated by the numeral 32, to receive therethrough a horizontally extending U-shaped catch or keeper 33 carried by a vertically extending plate 34 suitably attached to the post 25 as shown in Fig. 8.

The door jamb 21 is similarly formed from a vertically extending hollow post 35 which is externally covered by fabric material 36. Opposite end walls of the post 35 are provided with aligned apertures 37 and the post 35 receives therethrough a latch unit 38 which forms the es-

sence of the present invention. One of the handles 23 is provided with integral vertically spaced rods 39, one of which is shown, which extends through aligned apertures in the post 35 and latch unit 38 into the interior of the oppositely positioned handle 23 and are retained therein by clamping screws 40 received within groove-like portions 41 in the rods 39 near the ends thereof. The rods 39 function to fasten the oppositely positioned handles 23 and the latch unit 38 with respect to the post 35.

Near the upper portions of the handles 23 and latch unit 38 is a flat-sided pin 42 shown in Fig. 7. An end of the pin 42 is received within a key operated lock unit 43 suitably carried within one of the handles 23 and having a key-receiving face 44 flush with the outer surface of the handle 23. The center portion of the pin 42 extends through the latch unit in a manner to be described and the remaining end is received within an aperture 45 positioned centrally within a socket 46 rotatably carried in the oppositely positioned handle 23. The outermost end of the socket 46 is provided with an integral outwardly directed stud 47 which is received within an aperture in the knob 24, the knob being retained thereto by a clamping screw 48.

Referring to Figs. 2, 7 and 8, the outermost face of the post 35 carries a sealing strip mounting member 49 which is provided with outwardly and inwardly directed side walls defining oppositely positioned grooves 50 which have received therein radially projecting flanges 51 formed integral with a D-section sealing strip 52 of flexible rubber or plastic material. The sealing strip 52 is formed from an outwardly bowed U-shaped portion 53 integral with a substantially flat bottom cross member 54, the edge margins of which define the radially directed side flanges 51. The bottom cross member 54, including the side flanges 51, is held by the mounting plate 49 so that the central section thereof is bowed outwardly thereby placing the same under compression and utilizing the inherent resiliency of the material to urge the side flanges 51 into the interior of grooves 50. Upon the bringing of the door sections 15 and 16 into closed relation, the sealing bead defined by the U-shaped section 53 is received in the groove 31 of the cooperating sealing plate 30 carried by the post 25. This arrangement provides complete sealing between the door sections 15 and 16 when the same are brought into closed relation.

The elements forming the latch unit 38 will now be described in connection with Fig. 3 with reference being made to some additional views which better illustrate some of the parts. The latch unit 38 is formed from a housing 55 of flat rectangular shape as particularly shown in Fig. 9, the front wall of which is provided with oppositely directed, top and bottom edge extensions or flanges 56 which are suitably carried by the post 35 as shown in Fig. 8. The side walls of the housing 55 are provided with apertures 57 which are adapted to receive therethrough the positioning rods 39 previously described in connection with Fig. 2. Below the top aperture 57 are aligned apertures in the opposed side walls of the housing 55 which cooperatively carry the body portion of a cam 58 which is provided with a centrally located flat-sided aperture 59 of square outline adapted to receive therethrough the flat-sided pin 42 operated by the knob 24 as shown in Fig. 7. The cam 58 is provided with an outwardly directed camming finger 60 positioned within a substantially V-shaped groove 61 which is formed by a stamped projection 62 tapered toward one of its ends and integrally formed in a movable locking plate 63, the structural details of which are particularly shown in Fig. 11.

The plate 63 is provided centrally thereof with vertically spaced elongated apertures 64 which, as shown in Figs. 3 and 9, have mounted therein spaced pins 65 and 66, each of which is provided with a central annular groove defined by circumferentially continuous upstanding spaced end flanges 67. The pins 65 and 66 are fas-

tened to a side wall of the housing 55 by rivets 68 as shown in Fig. 9. The diameters of the flanges 67 in abutment with the inner surface of the wall of the housing 55 carrying the pins are slightly less than the width of the slots 64 so as to be received in the same and allow the plate 63 to slide vertically relative to the side wall within the housing 55.

A side margin of the plate 63 integrally carries a right angle flange 69 directed outwardly therefrom which defines an abutment stop means for a purpose to be described. Below the lowermost slot 64 the plate 63 is provided with spaced arcuate protrusions 70 which define with an intermediate flat neck a spring arm retaining portion. The lowermost margin of the plate 63 is provided with an integral downwardly extending flange arm 71 which extends outwardly of the bottom of the housing 55 through an opening therein as shown in Fig. 3.

As shown in Figs. 3 and 9, a spring arm 72 of a toggle spring 73 is received within the spring retaining portion of the plate 63 defined by the protrusions 70 and intermediate flat neck. The remaining spring arm 74 of the toggle spring 73 is free of the plate 63 and its endmost portion extends outwardly through the rear wall of the housing 55 for positioning within a slot 75 of inverted L-shape. In Figs. 9 and 10 the slot 75 is shown as being provided with a vertical leg 76 and a horizontal leg 77 extending at right angles to the top portion of the vertical leg 76. The toggle spring 73 is allowed to rotate about the longitudinal axis of its spring arm 72 relative to the plate 63 by reason of the spring arm 72 being loosely received within the protrusions 70 for a purpose to be described.

Intermediate the pins 65 and 66 and in association with the peripheral grooves of the same defined by the spaced flanges 67 is positioned a bolt or latch member 78. As particularly shown in Fig. 12, the latch member 78 has a body portion of substantial size provided with oppositely directed projections 79 and 80. The uppermost projection 79 defines with the body portion of the latch member 78 an arcuate shoulder 81 which is received in the groove in the uppermost pin 65 toward the rear face of the same and retained therein by the flanges 67. The lowermost projection 80 defines with the body portion of the latch member 78 an arcuate shoulder 82 which is received about the lowermost pin 66 within the groove carried thereby about the front portion thereof and being retained therein by the flanges 67. The mounting of the latch member 78 with respect to the pins 65 and 66 is particularly shown in Figs. 3-6 and in the functioning of the latch member, the pins 65 and 66 define pivot points about which the latch member 78 is allowed to pivot. Integral with the body portion of the latch member 78 is a forwardly directed latching portion 83 terminating in an integral downwardly directed finger or hook 84. The outermost or front surface 85 of the hook 84 is curved inwardly in a downwardly direction while the rearmost surface 86 of the hook 84 is substantially flat in a vertical plane. The front face or foremost surface of the body portion of the latch member 78 below the latching portion 83 is provided with a forwardly directed nub or abutment finger 87 which is adapted for abutment with the stop flange 69 carried by the plate 63.

Referring particularly to Figs. 3 and 8, the front wall of the housing 59 carries centrally thereof a bolt guide 88 which is provided with a vertically extending slot 89 within which is positioned the latching finger 84. Near the bottom portion of the vertical slot 89 is a transversely extending slot 90 which receives therein the catch 33 for locking relation with the finger 84. The vertical slot 89 extends well above the top surface of the latching portion 83 to allow upward movement of the same during engagement or disengagement with the catch 33. The outer top and bottom surfaces of the bolt guide 88 are provided with centrally positioned outwardly opening U-shaped grooves defined by arcuate bosses 91 which

confine therein the ends of the gasketing strips 52 as shown in Fig. 8.

The latch member 78 is urged into engagement with the spaced pins 65 and 66 by an inverted U-shaped spring 92 having one end thereof fixedly received within a spring retaining hole 93 (see Fig. 12) carried by the bottom projection 80 of the body portion of the latch member 78. The remaining end of the spring 92 is carried near the end of an adjustment screw 94 between a nut 95 threadedly received on the screw 94 and a cut-out flange portion 96 integral with a side wall of the housing 55 and bent at right angles with respect thereto. The end of the screw 94 is rotatably received within an aperture in the flange 96 and the nut 95 is held against rotation relative to the screw 94 by flat-sided contact with the inner surfaces of the spaced side walls of the housing 55. This arrangement is particularly shown in Fig. 2 and it will be noted that the head of the screw 94 is accessible through the vertical slot 89 in the bolt guide 88. As a result of this arrangement, the biasing strength of the spring 92 as applied to the latch member 78 may be regulated by rotating the screw 94 and advancing the nut 95 toward or away from the head of the same. The end of the spring 92 carried by the screw 94 is loosely received thereabout having its end bent in the form of an eye surrounding the screw 94 and the resiliency of the spring 92 is sufficient to maintain this end of the same in contact with the nut 95. Consequently, upon advancing the nut 95 toward the head of the screw 94 by rotating the same, the end of the spring carried by the screw 94 will follow the nut and the biasing strength of the same acting upon the latch member 78 will decrease. Similarly, movement of the nut 95 away from the head of the screw 94 will increase the biasing strength of the spring 92.

The action of the spring 92 on the latch member 78 by reason of the attachment of one of its ends adjacent the lowermost portion of the body portion of the latch member 78 urges the latch member in a counterclockwise direction thereby urging the arcuate shoulders 81 and 82 into contact with the surfaces of the grooves between the flanges 67 of the pins 65 and 66. The resilient urging of the latch member 78 into the position described maintains the finger 84 in its lowermost position within the vertical groove 89 of the bolt guide 88.

As shown in Figs. 3, 9 and 10, the spring arm 74 of the toggle spring 73 is held by the bottom edge of the vertical leg 76 of the inverted L-shaped slot 75 and in this position the arm 74 is spaced away from and below the arm 72 a substantial distance. The toggle spring 73 resiliently holds the plate 63 in its uppermost position and the bottom edges of the grooves 64 abut the bottom edges of the flanges 67 as shown in Fig. 9. The flange 71 is in its raised position in close association with the bottom wall of the housing 55.

In forcibly engaging the hook 84 with the catch 33, the front outer edge surface of the catch 33 is forced against the outer curved surface 85 and due to the curvature of the surface 85 the latch member 78 is forced upwardly about the bottom pivot point defined by the pin 66. The upward movement of the latch member 78 is illustrated in Fig. 3 by the broken line 97 and it will be noted that during the clockwise pivotal movement of the latch member 78 the spring 92 is compressed and the top projection 79 moves away from association with the center groove of the top pin 65. Regardless of the positioning of the arm 74 of the toggle spring 73, the raising of the finger 84 and clockwise pivotal movement of the latch member 78 about the pin 66 will always occur in response to the force coupling of the latch 33. Consequently, the door sections 15 and 16 may always be interlocked and the positioning of the arm 74 of the toggle spring 73 controls the manner in which the same becomes unlocked or unlatched for relative movement away from one another. As shown in Fig. 3, the abutment flange 69

carried by the plate 63 does not interfere with clockwise pivotal movement of the latch member 78 about the pin 66 as the abutment finger 87 of the latch member 78 moves in a clockwise direction upwardly and ultimately away from the inner surface of the abutment flange 69.

In Fig. 5 the functioning of the latch unit 38 to disengage the finger 84 from the catch 33 is shown. In order to bring this about it is necessary to move the plate 63 downwardly against the biasing action of the toggle spring 73 by turning the knob 24 and rotating the cam 58 and cam finger 60 in a clockwise direction as viewed. The camming finger 60 contacts the inner surface of the camming groove 61 and the plate 63 is moved downwardly against the biasing action of the toggle spring 73 to an extent that the upper edges of the grooves 64 abut the upper portions of the flanges 67 of the pins 65 and 66. With downward movement of the plate 63 the abutment flange 69 is moved downwardly out of abutting relation with the abutment finger 87 and the application of a force moving the door jambs 20 and 21 away from one another will cause the inner surface of the catch 33 to move outwardly against the inner surface 86 of the finger 84 and force the finger and associated latching portion 83 to move upwardly as illustrated. The application of force against the inner vertical surface 86 of the finger 84 in a direction away from the housing 55 acts against the biasing action of the spring 92 to move the lower projection 80 out of contact with the bottom pin 66 and cause the top curved shoulder 81 to pivot about the top pin 65. The abutment finger 87 moves forwardly and upwardly in a clockwise direction with respect to the pin 65 and with the abutment flange 69 moved out of interfering contact therewith, disengagement of the catch 33 and finger 84 is allowed.

Due to the positioning of the spring arm 74 a substantial distance below the arm 72, these arms will not come into or pass beyond dead center relation relative to one another upon the movement of the plate 63 in a downward position to an extent that the catch 33 may be forcibly disengaged from the latch member 78. In order to allow forcible disengagement of these elements it is necessary to operate the knob 24 against the biasing action of the toggle spring 73 and this spring will continuously urge the plate 63 and associated knob 24 back into their original positions. Consequently, upon the relieving of a twisting force applied to the knob 24 to allow forcible disengagement of the catch 33 and latch member 78, the biasing action of the toggle spring 73 will return the associated elements back into their original position and the abutment flange 69 will return into operative interference with the abutment finger 87. With the abutment flange 69 associated with the abutment finger 87 as shown in Fig. 3 the catch 33 may not be forcibly disengaged from the finger 84 as the application of force necessary to raise the latch member 78 to the position shown in Fig. 5 causes the abutment finger 87 to move toward the abutment flange 69 and upon abutting contact between these elements the latch member 78 is not allowed to move in a clockwise direction about the upper pivot point defined by the pin 65. The finger 84 is thereby prevented from being raised to an extent that the catch 33 may be moved out of engagement therewith.

The location of the pins 65 and 66 determine the force required to rotate the latch member 78 about either pin. The finger 84 is positioned relative to the pins 65 and 66 to cause the creation of a moment of force which moves the finger and body portion of the latch member 78 about a pivot point in the same direction of rotation when the catch 33 is moved forcibly relative to the finger 84 during engagement or disengagement of the finger 84 with the catch 33. The location of the pivot points defined by the pins 65 and 66 control the force required to produce the rotational movement of the latch member 78.

In Figs. 4 and 6 a different type of functioning of the latch member 78 is illustrated. The adjustment neces-

sary to bring about this different type of operation resides in the moving of the spring arm 74 of the toggle spring 73 upwardly into resting position within the horizontal leg 77 of the groove 75 as indicated by the reference numeral 98 in Fig. 10. As illustrated in Fig. 4, the retaining of the spring arm 74 in the horizontal leg 77 of the groove 75 brings the same into closer association with the arm 72 so that, upon downward movement of the plate 63 by the operation of the knob 24 and camming finger 60, the arm 72 moves into and beyond dead center relation with the arm 74 and ultimately into the position shown in Fig. 6. This movement reverses the biasing action of the toggle spring 73 so that instead of biasing the plate 63 in an upwardly direction, the plate is held in its lowermost position. Consequently, the abutment flange 69 is permanently held out of operative association with the abutment finger 87 and the catch 33 and finger 84 may be forcibly disengaged as previously described in connection with Fig. 5 without the necessity of forcibly holding the knob 24 to continuously overcome the biasing action of the toggle spring to an extent that the abutment flange 69 is held out of operative association with the abutment finger 87.

As shown in Fig. 4, forcible engagement between the catch 33 and latch 78 is brought about in exactly the same manner as previously described in connection with Fig. 3. The outermost edge of the catch 33 cams the latch member 78 to pivot about the lower pin 66 and move away from the upper pin 65 against the biasing action of the spring 92. The application of a twisting force to the knob 24 will move the cam finger 60 downwardly against the inner surface of the camming groove 61 and move the plate 63 downwardly to an extent that the spring arm 72 moves below dead center relation to the spring arm 74 and the biasing action of the toggle spring 73 is reversed. This reversal causes the plate 63 to be held in its lowermost position and as shown in Fig. 6. The application of force moving the catch 33 away from the finger 84 will cause the latch member 78 to pivot about the upper pin 65 and move out of contact with the lower pin 66. Thus the catch 33 and finger 84 may be forcibly disengaged.

The fixed positioning of the plate 63 by the toggle spring 73, as shown in Fig. 6, allows the catch 33 and finger 84 to become forcibly engaged and disengaged without the necessity of operating the knob 24. Consequently, it is necessary merely to apply oppositely directed forces to the handles 22 and 23 to latch and unlatch the door sections 15 and 16 and move the same relative to one another.

As shown in Fig. 7, the latch unit 38 may be locked against operation with respect to disengagement between the catch 33 and finger 84 by use of a known type of key-operated lock 43. However, it should be understood that in order to lock the latch unit 38 to prevent unlatching of the door sections 15 and 16 it is necessary to have the spring arm 74 positioned as shown in Fig. 3 or have it related with respect to the spring arm 72 as shown in Fig. 4. In other words, the locking of the flat-sided pin 42 against rotation by the knob 24 will not prevent disengagement between the catch 33 and hook 84 when the arms 72 and 74 of the toggle spring 73 are related to one another as shown in Fig. 6. The positioning of the elements as shown in Fig. 6 allows forcible engagement and disengagement of the catch 33 and hook 84 at all times and the locking of the flat-sided pin 42 against rotation will not affect the operation of the latch unit 38 except to prevent discontinued functioning in this manner by inadvertent turning of the knob 24 to move the arm 74 into the position shown in Fig. 4.

Referring to Fig. 8, an additional type of locking action may be relied upon which utilizes a key-operated lock 99 carried by a handle 23 below the latch unit 38 and controlling the movement of a locking arm 100 positioned within the post 35 and capable of being moved

into and out of abutting relation with the bottom flange 71 carried by the plate 63. As shown in Fig. 3, the lock 99 has been operated to move the locking finger 100 into abutting relation with the flange 71 and in the event that the knob 24 is turned in an effort to move the plate 63 downwardly to allow the catch 33 to be forcibly disengaged from the hook 84, the flange 71 will abut the finger 100 and prevent downward movement of the plate 63. Consequently, forcible disengagement between the catch 33 and hook 84 may not be obtained and unless the lock 99 is operated to move the finger 100 out of abutting relation with the flange 71 as shown in Fig. 5, the latch unit 38 may not be operated to allow forcible disengagement between the catch 33 and hook 84. This particular locking arrangement operates in exactly the same manner in connection with the positioning of the spring arm 74 of the toggle spring 73 as illustrated and described in connection with Figs. 4 and 6. Regardless of the adjustment made to the latch unit 38, it is necessary to move the plate 63 in a downward direction to allow the catch 33 to become forcibly disengaged from the hook 84. Therefore, as long as the flange 71 is locked against downward movement it is impossible to move the abutment flange 69 out of abutting relation with the abutment finger 87 to allow the latch member 78 to be pivoted about the uppermost pin 65.

From the foregoing description it is readily apparent that the latch unit 38 of the present invention is adapted for different uses. The latch unit 38 used with a door may be adjusted to allow the door to become engaged with a catch or disengaged therefrom merely by the application of force. Such a situation would utilize the latch unit 38 in the form as shown in Fig. 6. In the event that knob operation for opening the same is desired, the arrangement of Figs. 3 and 5 may be readily utilized. While the use of a single knob 24 has been illustrated, it should be understood that a knob can be placed in operative contact with both ends of the flat-sided pin 42 to allow the latch unit 38 to be operated from both sides of the door. Still further, in the event that a key-operated locking arrangement is desired, different arrangements may be applied to the latch unit 38 as described in connection with Figs. 3, 5 and 7. With respect to the key-operated lock 43 of Fig. 7, it should be further apparent that the turning of the key within the lock 43 will operate the knob 24 thereby allowing operation of the latch unit 38 from either side of the door.

Due to the adaptability of the latch unit 38 and the different modes of operation which may be utilized in connection with the same, the unit is readily adapted for use with both interior doors and outside doors. The end of the spring arm 74 protruding from the rear wall of the housing 55 may be made accessible through the exterior of the door section with which it is associated in the event that the operation of the latch unit 38 is desired to be converted during the use of the same. However, upon installation of the latch unit 38, adjustment of the same may be made to fit the needs of the purchaser and, in the event that the latch unit is permanently used with the arm 74 in one position only, no unusable parts are by necessity installed creating an unnecessary cost to the purchaser. This advantage arises from the fact that the arm 74 is a necessary element regardless of the manner in which the latch unit 38 is used.

Obviously many modifications and variations of the invention as hereinbefore set forth may be made without departing from the spirit and scope thereof, and therefore only such limitations should be imposed as are indicated in the appended claims.

I claim:

1. A door latch unit having a pivotally mounted latching member, said latching member including a body portion and a latching finger, said body portion being spring

urged into abutment with spaced members defining pivot points about which said latching member is adapted to pivot, a latching member abutment means movably associated with said body portion to limit pivotal movement of said latching member about one of said spaced members, and spring means associated with said latching member abutment means for biasing said abutment means into and out of limiting association with said latching member.

2. A latch unit including a latching member mounted for pivotal movement about spaced pivot points, which pivotal movement about any one of said points causes said latching member to move out of contact with the other of said points, said latching member including a latching hook adapted to be received over a portion of a catch brought into association therewith, said hook being related to said pivot points to allow engagement with and disengagement from a catch when said unit is forcibly moved relative thereto, and stop means movable into and out of pivotal movement limiting relation with said latching member to restrict forcible disengagement between said hook and a catch while allowing forcible engagement between the same.

3. A latch unit including a latching member mounted for pivotal movement about spaced pivot points, which pivotal movement about any one of said points causes said latching member to move out of contact with the other of said points, said latching member including a latching hook adapted to be received over a portion of a catch brought into association therewith, said hook being related to said pivot points to allow engagement with and disengagement from a catch when said unit is forcibly moved relative thereto, the foremost face of said hook being curved inwardly in a downwardly direction to provide upward movement of said latching member about one of its pivot points in response to force coupling of a catch therewith, and stop means movable into and out of pivotal movement limiting relation with said latching member to restrict forcible disengagement between said hook and a catch while allowing forcible engagement between the same.

4. A latch unit including a latching member mounted for pivotal movement about spaced pivot points, which pivotal movement about any one of said points causes said latching member to move out of contact with the other of said points, said latching member including a latching hook adapted to be received over a portion of a catch brought into association therewith, said hook being related to said pivot points to allow engagement with and disengagement from a catch when said unit is forcibly moved relative thereto, and stop means movable into and out of pivotal movement limiting relation with said latching member to restrict forcible disengagement between said hook and a catch while allowing forcible engagement between the same, said stop means being movable in conjunction with a toggle spring having a first arm operatively associated therewith and a second arm adapted for positioning in fixed biasing relation with said first arm and said stop means to continuously urge said stop means into operative relation with said latching member and for positioning relative to said first arm to allow the same to move in opposite directions past dead center relation with said second arm to allow movement of said stop means into and out of operative relation with said latching member.

5. A latch unit including a latching member mounted for pivotal movement about spaced pivot points, which pivotal movement about any one of said points causes said latching member to move out of contact with the other of said points, said latching member including a latching hook adapted to be received over a portion of a catch brought into association therewith, said hook being related to said pivot points to allow engagement with and disengagement from a catch when said unit is forcibly moved relative thereto, the foremost face of said hook

being curved inwardly in a downwardly direction to provide upward movement of said latching member about one of its pivot points in response to force coupling of a catch therewith, and stop means movable into and out of pivotal movement limiting relation with said latching member to restrict forcible disengagement between said hook and a catch while allowing forcible engagement between the same, said stop means being movable in conjunction with a toggle spring having a first arm operatively associated therewith and a second arm adapted for positioning in fixed biasing relation with said first arm and said stop means to continuously urge said stop means

5 into operative relation with said latching member and for positioning relative to said first arm to allow the same to move in opposite directions past dead center relation with said second arm to allow movement of said stop means into and out of operative relation with said latching member.

6. A latch unit comprising a housing, a latch member 20 formed from a body portion within said housing integral with a latching portion extending outwardly of said housing, said body portion being mounted between spaced pins and having substantially hook-like projections partially surrounding said pins and normally in engagement with the same to allow said latch member to pivot about each of said pins, spring means in said housing attached to said latch member to bias the body portion of the same into engagement with said pins, a movable plate carried by said pins and having mounted thereon an arm of a 25 toggle spring, the other arm of said toggle spring carried within a slot in said housing and having its free end extending outwardly of said housing, said plate being further provided with means associated with an externally positioned operating handle for moving said plate relative to said latch member, and an abutment means carried by said plate for movement thereby into and out of pivotal limiting association with said latch member, the 30 positioning of the other arm of said toggle spring in said slot controlling the action of the same with respect to 35 said plate in biasing said abutment means into and out of pivotal limiting association with said latch member.

7. The unit of claim 6 wherein the slot in the housing carrying the other arm of the toggle spring is provided with spaced spring arm retaining surfaces, one of said surfaces positioning said other arm in biasing relation with the first arm of said toggle spring to continuously urge the plate and abutment means carried thereby into pivotal limiting association with said latch member, the other of said surfaces positioning said other arm to 45 allow movement of said first arm with said plate in directions opposite of dead center relation between said arms for positioning of said abutment means in and out of pivotal limiting association with said latch member.

8. The unit of claim 6 wherein said hook-like projections extend above and below said body portion and partially surround vertically spaced pins to allow clockwise pivotal movement of said latch member about only one of said pins at any one time during the operation of said latch member.

60 9. The unit of claim 6 wherein said spring means have a portion fixed to said latch member and a portion fixed to adjustable means carried by said housing to regulate the biasing strength of said spring means.

10. A door handle and latch unit including a housing 65 carrying on an outer surface thereof a handle, a latch unit within said housing, said latch unit including a latch member formed from a body portion pivotally mounted between spaced pins and a latching portion extending outwardly of said housing, a movable plate carried by said pins and having pivotal limiting means for movement into and out of pivotal limiting association with said latch member, a toggle spring associated with said plate to partially control the positioning thereof, operating means carried by said handle and connected to said plate to move the same, and an abutment means carried by said

housing for movement into and out of movement limiting relation with said plate.

11. A door handle and latch unit including a housing carrying on an outer surface thereof a handle, a latch unit within said housing, said latch unit including a latch member formed from a body portion pivotally mounted between spaced pins and a latching portion extending outwardly of said housing, a movable plate carried by said pins and having pivotal limiting means for movement into and out of pivotal limiting association with said latch member, a toggle spring associated with said plate to partially control the positioning thereof, operating means carried by said handle and connected to said plate to move the same, and an abutment means carried by said housing for movement into and out of movement limiting relation with said plate, said abutment means including an abutment finger positioned within said housing and operated by a lock member carried by said handle.

12. A door latch unit having a pivotally mounted latching member including a hook and hook-carrying portion, said hook-carrying portion being spring urged into abutment with spaced members defining pivot points about which said latching member is adapted to pivot.

said hook being related to the pivot points so that either engagement or disengagement of the hook with a catch moved forcibly relative thereto results in a moment producing movement of said hook and hook-carrying portion about a pivot point in the same direction of rotation, each of said pivot points being positioned relative to said hook to control the force required to produce the rotational movement, and latching member movement limiting means adjustably associated with said latching member for movement into and out of abutting relation therewith to control pivotal movement of said latching member during the operation of said unit.
